PUMP

Jesse R. Lowry, Des Moines, Iowa

Application January 6, 1944, Serial No. 517,277

6 Claims. (Cl. 103—183)

This invention relates to improvements in reciprocating pumps and has particular reference to multiple cylinder pumps.

The principal object of this invention is the provision of a multiple cylinder reciprocating pump wherein the cylinders are formed in a single block and wherein all of the operating parts are removable from the open lower end of said block.

A further object of the invention is the provision of a multiple cylinder reciprocating pump having guided outside plunger rods which are motor driven from the top of the well.

Other objects are simplicity and economy of construction, ease and efficiency of operation, and adaptability for general use where a constant flow of water is desired.

With these objects in view, reference will now be had to the drawings, wherein:

Figure 1 is a foreshortened elevational view of a multi-cylinder reciprocating pump shown in position in a well hole, embodying this invention.

Fig. 2 is an enlarged elevational view partly in section of the upper portion of the pump.

Fig. 3 is an enlarged elevational view partly broken away of the motor driving gears.

Fig. 4 is a sectional view taken on line IV—IV of Fig. 6.

Fig. 5 is a cross sectional view taken on line V—V of Fig. 6.

Fig. 6 is an enlarged sectional view of the pump cylinders and valves.

Fig. 7 is an enlarged elevational view of the pump cylinders.

Fig. 8 is a modified form of the pump structure wherein a strainer is provided.

Fig. 9 is an elevational edge view of the pump cylinder.

Fig. 10 is a cross sectional view taken on line X—X of Fig. 8.

Throughout the several views, like reference characters refer to similar parts and the numeral 10 designates a well pipe extending from adjacent the bottom of the well hole 12 to a pipe coupling 14 which communicates with a transverse pipe 16 then by vertical pipe 18 to any desired point above the ground level. These pipes are so constructed that the water from the cylinder block 20 adjacent the bottom of the well, will travel upwardly through pipe 10, transverse pipe 16, thence through vertical pipe 18 to the point of use. Cylinder block 20, best shown in Fig. 6, is provided with parallel cylinders 22 and 24. The axes of these cylinders are parallel with

the axis of the well pipe 10 and are provided with outlet check valves 26 and 28 respectively. These check valves are mounted concentrically in cylinders 22 and 24 respectively and are disposed in the upper chamber 30 of the cylinder block. This chamber 30 communicates with well pipe 10 as clearly shown. It will be noted that this valve construction is so designed and mounted that it may be easily mounted in the cylinder block or removed therefrom by the simple operation of removing a screw 32 which is threaded into a blind recess 34 formed in the upper end portion of the cylinder block. The head 36 of screw 32 engages the disc valve set member 38 to force it to position against the shoulder 40 formed in cylinder block 20 with a suitable valve gasket 42 positioned therebetween. The valve 26 is adapted to slide on the plane section 44 of screw 32 and to contact an adjustable stop nut 46 which may be adjusted to any desired position to limit the upward movement of valve 26.

It will be noted that valve 26 is provided with a hub 48 which is recessed at 50 so that the valve may move to contact stop nut 46 without any interferences from the threads 51. Valve 28 is similarly constructed and mounted so as to operate in like manner.

An operating piston 52 comprises a hollow body member 54 offset and threaded at 56 to receive 30 a nut 58 by means of which is secured the piston gasket 60. This gasket 60 is preferably made of leather or some similar material which will resist wear and will tend to seal the piston in the cylinder.

35 It will be noted that the pump rods 62 and 64 are formed so as to enter the cylinders from their open bottom ends to securely engage the centrally disposed sleeve 66 which is secured by the radial spokes 68 to the piston body 54. The threaded portion 70 of pump rod 62 is slightly reduced to present a shoulder 72 which engages the lower side of sleeve 66 and the upper end of pump rod 62 is reduced at 74 to receive the slidably mounted valve 76. This valve is recessed at 78 to receive the nut 80 which engages the upper end of 74 to limit the upward travel of valve 76. This valve construction presents a compact valve which can be moved in the cylinder close to the check valve 26, thus making it possible to deliver substantially all the water from the respective cylinders to the well pipe 10. Since in some instances the pump rods 62 and 64 will be of considerable length, it is found necessary to properly guide these rods adjacent the pistons. For this purpose the tubular ears

82 adjacent the top of the cylinder block and ears 84 adjacent the bottom thereof serve to maintain the pump rods in axial alignment with the movement of the pistons in the cylinders. These pump rods 62 and 64 extend upwardly to a point adjacent the top of the well and are provided with a guide block 86 and are respectively connected with pitman rods 88. These pitman rods are pivoted to the diametrically disposed crank arms 90 which are rigidly attached to a shaft 92 which is driven by spur gear 94. A spur pinion 96 mounted in the gear housing 98 is in mesh with gear 94 and is driven by motor 100 through pulley 102 and pulley 104 interconnected by means of belt 106. When so driven, the pistons in the cylinder block 20 will be oppositely reciprocated at all times so as to produce a continuous flow of water from the well pipe 18, a continuous flow of water from the well pipe 18, and as one of the cylinders is being emptied the other will be filling.

Attention is called to the one piece cylinder block 20 which is so constructed that the cylinders may be bored from the open end, shoulder 40 will simultaneously be formed and while the cylinder is still in axial alignment with the finishing tool, recess 34 may be bored and tapped to receive the machine screw 32. The upper end of the casting may be centered, bored and tapped to receive the well tubing 10 from above.

It is quite apparent that this structure is very sturdy, simple and easily machined, thus producing a very inexpensive and efficient pump construction.

The tubular ears 82 and 84 integral with the cylinder block, serve to maintain the U-shaped lower portions thereof in proper axial alignment with the cylinder.

Reference will now be had to the modified form shown in Figs. 8, 9 and 10 wherein the general construction of the pump is similar to that shown in the preferred form except for a modified form of the piston and the piston rods.

The piston 110 is provided with a body member 112 reduced at 114 and threaded at 116 to receive the internal threads 118 of the valve seat 120. Valve body member 110 is provided at its lower extremity with a screen cage 122 about which is circumscribed a cylindrical screen 124 through which the fluid to be pumped must pass before entering the pump cylinders. Valve seat 120 is provided with a central body portion 126 in which is mounted an axially disposed screw 128, the body of which serves as a guide for the valve 130. Furthermore, the head of the bolts serves to limit the opening movement of the valve. The valve gasket 132 has an inturned flange 134 which is disposed between the body member 112 and the valve seat 120. The outside diameter of the screen 124 is slightly smaller than the inside diameter of the cylinder, thus permitting free movement of the screen portion of the piston into the piston as indicated in Fig. 8. The piston rod comprises a U-shaped structure 136 which straddles the respective cylinders with its lower threaded ends extended through the lower flanges 138 of the body member 112. The upper end of 136 is adapted to receive the operating rod 140 to which it is secured by means of nuts 142. The bifurcated portions 144 of member 136 are adapted to slide through the sleeves 146 made integral with the cylinder block 20. This type of connecting rod for the piston insures a proper centering of the piston during its travel into the cylinder and also prevents accidental bending of the rods.

The means for driving the piston rods might be varied to produce their proper reciprocation without departing from the spirit of this invention.

Having thus described the invention, what I claim as new and desire to be secured by Letters Patent is:

1. A double acting pump comprising a unitary cylinder block having a pair of open end cylinders and a chamber formed therein, a piston mounted in each of said cylinders, a well pipe communicating with said chamber, valves and valve seats controlling the flow of fluid from said cylinders to said chamber, a screw extending upwardly through each of said valve seats and threaded into said cylinder block whereby said valve seats and valves are removably mounted in said cylinders, a J-shaped piston rod engaging each of said pistons respectively and extending below said cylinder block and through apertured ears carried by said cylinder block, and driving means at the top of the well operable to successively operate said pistons to force fluid through said well pipe.

2. A double acting pump comprising a unitary cylinder block having a top chamber communicating with the well pipe, and having a pair of open end cylinders provided at their upper ends with an inturned annular flange, a valve seat positioned in each of said cylinders against said flanges, a screw engaging each of said valve seats and extended through said chamber to engage a threaded recess formed in the cylinder block to force said valve seat against said flange, a valve mounted in each of said valve seats operable by liquid pressure to permit the flow of liquid from said cylinders to said chamber, a valved piston mounted in each of said cylinders, and means operable to cause said pistons to successively move to force liquid through said well pipe.

3. A double acting pump comprising a unitary cylinder block having a top chamber communicating with the well pipe, and having a pair of open end cylinders provided at their upper ends with an inturned annular flange, a valve seat positioned in each of said cylinders against said flanges, a screw engaging each of said valve seats and extended through said chamber to engage a threaded recess formed in the cylinder block to force said valve seat against said flange, a valve mounted in each of said valve seats operable by liquid pressure to permit the flow of liquid from said cylinders to said chamber, a valved piston mounted in each of said cylinders, and means, including J-shaped piston rods, a motor, speed reduction gears interconnecting said motor with said piston rods, whereby said pistons are successively reciprocated to force liquid through said well pipe.

4. In a reciprocating type pump, a unitary cylinder block having an upright cylinder therein open at the lower end of the block, with said open end of the cylinder constituting an inlet for said pump, chamber means at the upper end of said block communicating with said cylinder and with a discharge pipe for said pump, valved piston means operatively associated with said cylinder and receivable in said cylinder through the open end thereof, an annular shoulder adjacent the upper end of said cylinder, valve means for controlling the flow of fluid from said cylinder located in said chamber means and including an open annular valve seat engageable with the under side of said shoulder, screw means extended upwardly through said valve seat and threadable

in the top wall of said chamber means to hold said valve seat against said shoulder, and a valve member movably supported on said screw means for movement into and out of a seating relation with said valve seat, with said valve means being removable through the open end of said cylinder on disengagement of said screw means from the top wall of said chamber means.

5. In a reciprocating type pump, a unitary cylinder block having an upright cylinder therein open at the lower end of the block, with said open end of the cylinder constituting an inlet for said pump, chamber means at the upper end of said block communicating with said cylinder and with a discharge pipe for said pump, valved piston means operatively associated with said cylinder and receivable in said cylinder through the open end thereof, an elongated screen member carried by said valved piston, whereby all fluid passing through said valved piston to said cylinder will pass through said screen, an annular shoulder adjacent the upper end of said cylinder, valve means for controlling the flow of fluid from said cylinder located in said chamber means and including an open annular valve seat engageable with the under side of said shoulder, screw means extended upwardly through said valve seat and threadable in the top wall of said chamber means to hold said valve seat against said shoulder, and a valve member movably supported on said screw means for movement into and out of a seating relation with said valve seat, with said valve means being removable through the open end of said cylinder on disengagement of said screw means from the top wall of said chamber means.

6. In a reciprocating type pump, a unitary cylinder block having an upright cylinder therein open at the lower end of the block, with said open end of the cylinder constituting an inlet for said pump, chamber means at the upper end of said block communicating with said cylinder and with a discharge pipe for said pump, valved piston means operatively associated with said cylinder and receivable in said cylinder through the open end thereof, an elongated screen member carried by said valved piston, whereby all fluid passing through said valved piston to said cylinder will pass through said screen, an annular shoulder adjacent the upper end of said cylinder, valve means for controlling the flow of fluid from said cylinder located in said chamber means and including an open annular valve seat engageable with the under side of said shoulder, screw means extended upwardly through said valve seat and threadable in the top wall of said chamber means to hold said valve seat against said shoulder, and a valve member movably supported on said screw means for movement into and out of a seating relation with said valve seat, with said valve means being removable through the open end of said cylinder on disengagement of said screw means from the top wall of said chamber means, and a bifurcated piston rod straddling said cylinder and engaging opposite edges of the lower extremity of said screen member whereby said piston is reciprocated as said piston rod is reciprocated.

JESSE R. LOWRY.
